CONVERSION OF HYDROCARBONS

Rowland C. Hansford and Alexander N. Sachanen, Woodbury, N. J., assignors to Socony-Vacuum Oil Company, Incorporated, a corporation of New York

No Drawing. Application August 9, 1944,
Serial No. 548,786

3 Claims. (Cl. 196—52)

1

This invention relates generally to cracking of petroleum stocks, and is more particularly concerned with a method of catalytic cracking of petroleum stocks, whereby the yields of hydrocarbons boiling within the gasoline boiling range, are substantially increased.

Cracking is a well known chemical process and generally connotes operations for converting heavy hydrocarbon molecules into light hydrocarbon molecules. The decomposition or the breakdown of the heavy hydrocarbon molecules into lighter ones, is accompanied by the concurrent formation of even heavier hydrocarbon molecules and by the production of solid material referred to as coke. Cracking was originally carried out non-catalytically, at temperatures of the order of 750-1100° F with the charge stocks mostly in the liquid phase. However, due to the demand for anti-knock gasoline, and since the motor fuels produced by catalytic cracking operations, possess anti-knock properties superior to those of motor fuels produced by non-catalytic or thermal cracking, catalytic cracking soon came into prominence. The development of aviation soon created a demand for motor fuels having not only anti-knock characteristics superior to those of motor fuels produced by thermal cracking, but possessing also more desirable overall properties and, particularly, a greater stability with reference to gum formation during use and storage.

It is well known to those familiar with the art, that catalytic cracking of petroleum stocks has been carried out mostly in the vapor phase and has been predicated, for the most part, on the use of cracking catalysts that form with the charge in the cracking zone, a heterogeneous system.

It is well known also, that the charge stocks for use in the catalytic cracking operations of the prior art, have been selected petroleum stocks. Heavy residual stocks and virgin stocks of a refractory nature have not been suitable for catalytic cracking operations due to their inherent coke-forming characteristics and to their resistance to cracking to form hydrocarbon fractions

2

having desired boiling ranges. As a consequence, the supply of available catalytic cracking stocks is restricted.

As is well known in the art, even recycle stocks obtained from the catalytic cracking of non-refractory petroleum cracking stocks, are not suited to recycling to the catalytic cracking zone to be subjected to the catalytic cracking operation per se or in conjunction with the charge stocks, due to their somewhat refractory nature. Accordingly, these recycle stocks frequency have been processed separately, in thermal cracking operations, as distinguished from cracking operations wherein cracking catalysts are employed. As noted hereinbefore, gasoline produced by catalytic cracking operations is somewhat superior to gasoline produced by thermal cracking operations. Hence, and in view of the foregoing, only a moderate portion of the total yield of hydrocarbons boiling within the gasoline boiling range, may be obtained as superior catalytically cracked gasoline, while the rest is the somewhat inferior thermally cracked gasoline.

In view of the present and future necessity to produce the highest possible yield of high quality motor fuels from petroleum, the importance of a method of catalytic cracking of petroleum stocks, whereby the total yields of catalytically cracked gasoline, are materially increased, is manifest.

30 We have found that when a petroleum stock is subjected to catalytic cracking in the presence of a thermally stable aromatic hydrocarbon, the total yields of hydrocarbons boiling within the gasoline boiling range, are markedly increased.

35 The present invention is to be distinguished from those processes for the production of aromatic hydrocarbons from the cracking of petroleum oils, wherein in order to minimize the production of benzene in preference to alkyl aromatic hydrocarbons, the concentration of benzene is increased above that produced by the normal formation of benzene in the cracking zone. The present invention is not directed to a process for the production of aromatic hydrocarbons or of cyclic hydrocarbons, but rather, it is directed to

an improved catalytic cracking operation for the production of high yields of hydrocarbons boiling within the gasoline boiling range. It must be noted that the gasoline produced in accordance with the present invention, is the somewhat superior product or that resulting from catalytic cracking operations.

Accordingly, it is an object of the present invention to provide a method for converting heavy liquid hydrocarbons into light, normally liquid hydrocarbons. Another object is to provide an improved method of catalytic cracking. A further object is to afford an efficient method for effecting the catalytic cracking of petroleum stocks of a refractory nature. A very important object is to provide a method of catalytic cracking, whereby the total yields of catalytically cracked gasoline are materially increased. A more specific object is to provide a method of catalytic cracking capable of carrying out the foregoing objects by subjecting petroleum cracking stocks to catalytic cracking in the presence of thermally stable aromatic hydrocarbons. Other objects and advantages of the present invention will become apparent to those skilled in the art from the following description.

Broadly stated, our invention provides a method for converting heavy, normally liquid hydrocarbons into light, normally liquid hydrocarbons, which comprises contacting said heavy, normally liquid hydrocarbons under cracking conditions, with a cracking catalyst, in the presence of an added aromatic hydrocarbon that is thermally stable under said cracking conditions.

According to our invention, any aromatic hydrocarbon which is stable at the temperatures ordinarily used in thermal and catalytic cracking operations, is suitable for our purpose. Benzene, methyl benzene, naphthalene, and diphenyl may be mentioned by way of non-limiting examples of the aromatic hydrocarbons employed.

In the preferred embodiment of our invention, we use benzene as the thermally stable aromatic hydrocarbon. Accordingly, benzene may be charged together with the petroleum cracking stock, into the cracking zone. In the cracking zone, the stock is subjected to the cracking conditions and converted in the desired manner. The benzene vapors emerge from the cracking zone unchanged along with the products of the cracking operation, and together, they are sent through a fractional condensation system to condense the desired fractions of lower-boiling hydrocarbons that have been produced, and, also, a benzene fraction. The benzene fraction ordinarily constitutes a substantially complete recovery of benzene, and this fraction may be conveniently recycled to the cracking zone with fresh petroleum cracking stock.

Generally speaking, the conversion of heavy, normally liquid hydrocarbons into light, normally liquid hydrocarbons by pyrolysis, with or without the use of cracking catalysts, at temperatures of the order of about 800° F. to about 1100° F., and at pressures determined by the phase of operation, may be carried out advantageously, in the presence of added benzene. If desired, the added benzene may be substantially completely recovered, and used with fresh petroleum stocks.

In our method, we recommend the use of upwards of about $\frac{1}{2}$ volume of benzene to 1 volume of petroleum stock, and preferably, between $\frac{1}{2}$ to about 2 volumes of benzene to 1 volume of petroleum stock.

The charging stocks to be treated in accordance

with the method of our invention, are any of the well known petroleum cracking stocks for thermal cracking or catalytic cracking operations, although the advantages of the method of the present invention, are more predominant when the heavier and more refractory petroleum cracking stocks are employed. For instance, benzene can be used to advantage in the cracking of heavy residua for the sole purpose of gasoline production. For example, the cracking of heavy petroleum residua, of the order of A. P. I. gravity 10 and lower, is performed with considerable difficulty because of excessive coke formation. The use of fractions from these heavy residua as the recycling stock for such cracking operations, does not give satisfactory results, since these fractions themselves have undesirable coke-forming properties. On the other hand, the use of other recycle stocks having higher A. P. I. gravity, for such cracking operations, is practically impossible due to the fact that the rate of cracking of these latter stocks is much higher than that of the heavy residua. Benzene, however, is highly refractory and accordingly, does not form coke under the cracking conditions; as a matter of fact, benzene actually tends to diminish coke formation. As stated hereinbefore, benzene can be recovered and recycled and, particularly because of its tendency to reduce coke formation, it constitutes an attractive additive in catalytic cracking processes where the amount of coke deposit regulates the requirements for catalyst regeneration.

A feature of the method of the present invention, is that the yields per pass of hydrocarbons boiling within the gasoline boiling range, other variables such as temperature, contact time of the petroleum stock in the catalyst bed, etc., remaining constant, are unusually high. The prior art did not successfully crack heavy stocks under the temperature conditions of the present invention. Such high temperature conditions in the absence of added benzene lead to very excessive coke and gas formation with resultant low yields of gasoline.

Accordingly, another feature of our method, is that severe cracking conditions may be employed. It is well known that the octane number of motor fuels increases rapidly with increasing severity of cracking. However, severe cracking conditions are normally avoided in conventional commercial operations due to practical considerations arising from excessive coke and gas formation. The use of benzene, as set forth hereinbefore, minimizes coke and gas formation; hence, our invention provides a method for producing motor fuels having higher octane ratings from otherwise similar petroleum cracking stocks, that is practical and commercially feasible.

A very important feature of the present invention, is the low consumption of benzene in the overall reaction. With some petroleum stocks there is an appreciable consumption of benzene amounting to about 5% of the stock being processed. In other cases, however, the consumption is practically nil. This would seem to indicate a behavior, on the part of benzene, not unlike that of a catalyst, within the broad meaning of the term. Without any intent to limit the scope of the present invention, it is our belief that benzene enters into the cracking reaction during the early stages of the operation, by functioning as a hydrogen and alkyl radical "acceptor," and is subsequently regenerated by dehydrogenation and dealkylation.

A most important feature of this invention, is that by our method, catalytic cracking of refractory stocks is rendered commercially feasible. Even extremely refractory stocks of the type produced in thermal cracking and reforming operations, gives quite satisfactory yields of gasoline as compared to those obtainable in processes of the prior art.

To illustrate the method of our invention and to

total charge (benzene-stock) or of 0.167 based on the cracking stock. Under similar conditions, but in the absence of benzene, such a cracking stock would be so severely cracked that the yield of gasoline probably would be no more than 20-25%, while the yield of coke and gas would be very high. The use of very severe conditions of catalytic cracking, such as 925° F. and a space velocity of 0.167, in the presence of benzene, is an advantage of the method of our invention.

¹ Benzene was carefully fractionated out of gasoline cut in range 70-95° C. and analyzed for purity. Impurities are included in gasoline yield and amount to about 10% of total gasoline cut.

These data illustrate one of the most striking features of the method of our invention, namely that even extremely refractory charge stocks give satisfactory yields of gasoline.

The figures given on the recovery of pure benzene can be considered to be quite reliable if the basic assumption that benzene does not contribute to gas and coke formation, is correct. This assumption was verified by runs with benzene alone and is valid at temperatures below about 950° F. and in the range of space rates indicated.

This application is a continuation-in-part of our copending application Serial Number 366,806, filed November 23, 1940, now abandoned.

Although the present invention has been described in conjunction with preferred embodiments, it is to be understood that modifications and variations may be resorted to without departing from the spirit and scope of the invention, as those skilled in the art will readily understand. Such variations and modifications are considered to be within the purview and scope of the appended claims.

We claim:

1. A method for obtaining high yields of hydrocarbons boiling within the gasoline boiling range from a recycle petroleum cracking stock having an A. P. I. gravity of less than about 15°, which comprises contacting a mixture consisting essentially of said recycle petroleum cracking stock and added benzene in amounts varying between about $\frac{1}{2}$ to about 2 volumes of added benzene to one volume of said recycle petroleum cracking

stock, under conditions of catalytic cracking.

2. A method for obtaining high yields of hydrocarbons boiling within the gasoline boiling range from a recycle petroleum cracking stock having an A. P. I. gravity of less than about 15°, which comprises contacting a mixture consisting essentially of said recycle petroleum cracking stock and added benzene, in amounts of at least about one-half volume of added benzene to one volume of said recycle petroleum cracking stock under conditions of catalytic cracking including a temperature varying between about 800° F. and about 1100° F., with a catalyst promoting cracking under said conditions of catalytic cracking.

3. A method for obtaining high yields of hydrocarbons boiling within the gasoline boiling range from a recycle petroleum cracking stock having an A. P. I. gravity of less than about 15°, which comprises contacting a mixture consisting essentially of said recycle petroleum cracking stock and an added aromatic hydrocarbon selected from the group consisting of benzene, alkyl benzene, naphthalene, and diphenyl, in amounts of at least about one-half volume of added aromatic hydrocarbon to one volume of said recycle petroleum cracking stock, under conditions of catalytic cracking including a temperature varying between about 800° F. and about 1100° F., with a catalyst promoting cracking under said conditions of catalytic cracking.
